J. F. TRASK

MATTRESS

Filed March 2, 1925

INVENTOR.

JAMES FRANCIS TRASK

BY

Edmund F. Trask

ATTORNEY.

UNITED STATES PATENT OFFICE.

JAMES FRANCIS TRASK, OF LOS ANGELES, CALIFORNIA.

MATTRESS.

Application filed March 2, 1925. Serial No. 12,688.

To all whom it may concern:

Be it known that I, JAMES FRANCIS TRASK, a citizen of the United States, residing at Los Angeles, in the county of Los Angeles and State of California, have invented a new and useful Improvement in Mattresses, of which the following is a specification.

This invention relates more specifically to a means for preventing the fabric covering (ticking) of a mattress from stretching during its use.

In the construction of mattresses for sleeping purposes it is generally the custom to employ a fabric container, commonly known as a "tick", for maintaining in position layers of felt, cotton, hair, or other filling material, the horizontal fabric members being tied or tufted together at uniform intervals throughout their entire surface by means of vertically disposed cords, some of the tufted effects being termed "biscuit" or "diamond" tufts. The tufting of mattresses is not only highly desirable for the reason that it prevents shifting of the flexible filling material, but it also helps to preserve their original slightly appearance and uniform contour for a considerable length of time. Oftentimes the portions of such mattresses adjacent their edges after long continued use become distorted or stretched out of shape, the side and end edges being irregular in form, these deformations being occasioned by a "matting" or "compacting" of the flexible filling due to constant use, and the fabric coverings stretching to their original area.

By means of the hereinafter described construction the above noted disadvantages are largely obviated, the non-stretching fabric members attached only at their edges to the oppositely disposed faces of the horizontally disposed fabric members, and being of less area than said members serve to prevent their stretching to their original area by the compressing of the flexible filling.

It is therefore an object of this invention to provide a device which when secured to a mattress covering or "tick" will prevent its distortion or deformation from the original configuration during use.

Other objects and advantages will become apparent from the following specification, reference being had to the drawings accompanying the same, in which:

Fig. 1 is a perspective view of a portion of a sleeping mattress provided with the non-stretching cover device.

Fig. 2 is a face view of a complete mattress with parts of the outer face covering broken away to disclose the non-stretching cover device. 65

Fig. 3 is an enlarged partial transverse section of a mattress showing one of the tufted portions.

Fig. 4 is an enlarged partial face view of a mattress showing the non-stretch device 70 in position.

Fig. 5 is a diagrammatic view of one of the face covers showing the non-stretch cover secured thereto.

Fig. 6 is a similar view showing the face 75 cover in its contracted or tufted position, and the non-stretch member disposed therebelow.

Fig. 7 is a similar view of one of the cover members, and its non-stretch member. 80

Referring more specifically to the drawing, 10 designates a mattress of usual form, consisting of a flexible filling 11, preferably formed of layers of cotton fibre, felt, or hair, enclosed by a fabric cover consisting of horizontally disposed cover members 12, 13, and vertically disposed side and end fabric walls 14, 15, 16, 17, respectively connected to said horizontal cover members along their edges. 85

In order to prevent a shifting of the flexible filling material, and to preserve the original contour of the mattress as long as possible, the two horizontal cover members 12, 13, are tied together at suitable intervals throughout their area by means of a plurality of vertically disposed cords 20, producing the well known "biscuit tufts" effect on the outer faces of said members. 90

The length and width of the horizontal fabric covers 12, 13, are cut considerably 100 larger than the length and width of the finished mattress in order to provide sufficient fullness of material to permit of the tufting operation.

After the finished mattress has been used 105 a short time, the flexible filling becomes compacted to such an extent as to cause the fabric covers 12, 13, to stretch or flatten out to their original size, causing a deformation of the mattress, the side edges particularly 110 overhanging the side rails of the bed on which it is disposed and causing an unsightly appearance. In order to overcome this objectionable feature, each of the inner oppositely disposed faces of the fabric covers 12, 13, is provided with a fabric sheet 21, 22, preferably formed of a substantially 115

non-stretchable material, the sheets being secured to the covers by stitching 23, along their edges. The length and width of these sheets are exactly the same as the length and width of the finished mattress. In order that the vertical tufting cords 20, will not in any manner engage or interfere with the fabric sheets 21, 22, each sheet is provided with a plurality of circular holes 24, spaced apart in rows so that when secured in position on the fabric members 12, 13, they will register with the tufting cords. The circular holes 24, are preferably stitched around their edges to prevent undue ravelling.

15 From the above description it will be at once apparent that by securing to each of the inner faces of the fabric cover members a fabric sheet of an area corresponding to the area of the finished mattress, that when the 20 flexible filling material is compacted by reason of constant use the fabric sheet members will prevent the outer cover members from stretching to their initial size, and as a result the mattress will not be deformed in 25 the slightest degree.

In Fig. 5, one of the mattress cover members and its non-stretch sheet is shown diagrammatically to illustrate the relative width of the two members, the fullness of 30 the outer cover member being taken up by the tufting, and as a result the width of both members are equal.

What I claim is:

1. A mattress construction comprising top 35 and bottom fabric coverings connected by side and end fabric walls, a flexible filling enclosed by said coverings, a plurality of vertical tufting cords connecting the top and bottom cover members and passing through 40 the flexible filling, and a fabric sheet of

smaller area than the top and bottom coverings secured to their oppositely disposed faces along their edges and out of contact with the tufting cords, whereby when the filling of the mattress is compacted by use 45 of the fabric sheets will prevent the top and bottom fabric coverings from stretching.

2. A mattress construction comprising top and bottom fabric covers spaced apart and having side and end fabric walls connecting 50 the same, a flexible filling enclosed by said covers, a plurality of vertically disposed cords connecting said top and bottom covers passing through the flexible filling material 55 to form tuftings on the horizontal faces of said mattress and to prevent a shifting of the mattress filler, and means secured only along the edges of the top and bottom covers and out of contact with the tufting cords to prevent stretching of the same during the use 60 of the mattress.

3. A mattress construction comprising top and bottom fabric covers spaced apart having side and end fabric walls connecting the 65 same, a flexible filling enclosed by said coverings, a plurality of vertically disposed tufting cords connecting the top and bottom covers, and a fabric sheet of less area than the top and bottom covers secured to their oppositely disposed faces along the edges, 70 said fabric sheets having a plurality of holes formed therein and registering with the tufting cords, whereby the cords may pass from the top to the bottom cover without engaging the fabric sheets.

In witness that I claim the foregoing I have hereunto subscribed my name this 16th day of February, 1925.

JAMES FRANCIS TRASK.
